POWERED HAND-HELD AUTOMOBILE VACUUM CLEANER

Harold Richards, Eastchester, and Jean J. Schnoll, New York, N.Y., assignors to Perfect Film & Chemical Corporation

Filed Feb. 8, 1967, Ser. No. 5,725

Term of patent 14 years

(Cl. D9—2)

FIG. 1

FIG. 2

FIG. 3

FIG. 4

FIG. 5

FIG. 1 is a side elevational view of a powered hand-held automobile vacuum cleaner showing my new design, the opposite side being identical;

FIG. 2 is a top plan view thereof;

FIG. 3 is a bottom plan view thereof;

FIG. 4 is a front elevational view thereof; and,

FIG. 5 is a rear elevational view of the powered hand-held automobile vacuum cleaner.

I claim:

The ornamental design for a powered hand-held automobile vacuum cleaner, as shown and described.
